UNITED STATES PATENT OFFICE.

WILLIAM PAULMANN AND HENRY PAULMANN, OF GLASTONBURY,
CONNECTICUT.

STOP-MOTION FOR SEWING AND LOOPING MACHINES.

SPECIFICATION forming part of Letters Patent No. 417,333, dated December 17, 1889.

Application filed October 3, 1888. Serial No. 287,069. (No model.)

To all whom it may concern:

Be it known that we, WILLIAM PAULMANN and HENRY PAULMANN, citizens of the United States, and residents of Glastonbury, in the county of Hartford and State of Connecticut, have invented certain new and useful Improvements in Stop-Motions for Sewing and Looping Machines, of which the following is a full, clear, and exact description, whereby 10 any one skilled in the art can make and use the same.

Our invention consists in the combination of the frame, the movable head, the belt-shifter rod, and a stop-motion device. It further consists in the combination, in a machine of this class, of the movable head bearing a trip device, a stop-rod with a projection in the path of movement of the trip, and a tilting lever that is connected to the stop-rod 15 and to the shifter-bar; and it further consists in the details of the several parts of the device making up our improvement, and in their combination, as more particularly hereinafter described, and pointed out in the 20 claims.

Referring to the drawings, Figure 1 is a view in rear elevation of a sewing-machine with our improvement attached. Fig. 2 is a detail view, in rear elevation, on an enlarged scale, 25 illustrating the operation of our device. Fig. 3 is a detail side view of the trip-finger borne on the sewing-machine head. Fig. 4 is a detail top view of the adjustable trip-finger.

In the accompanying drawings, the letter 30 *a* denotes the bed of a seaming-machine such as is shown and described in United States patent to E. E. Kilbourn, dated November 20, 1866, No. 59,746, this machine having a movable head *b*, carrying the thread and part of 35 the sewing and looping mechanism, the said head being driven by means of the threaded shaft *c*, that extends from end to end across the bed, and is driven, as by means of a belt *d*, passing around the pulley *d'*. In the ordinary method of using this machine the movement of the head *b*, that is driven by the screw-shaft *c*, is stopped by means of a shipper-rod *e*, that extends along the machine 40 above the shaft in a position where it may 45 be conveniently reached by the operator from any point along the length of the machine.

This shipper-rod is supported in bearings *f f'*, and has at one end a shoulder *g*, that abuts against the bearing *f* when the belt is running on the fast pulley. The machine is stopped 55 by lifting up on the shipper-rod, when the spring *h* at once moves it lengthwise and throws the belt *d* upon the loose pulley and stops the machine.

Owing to inattention or carelessness or 60 the effort to attend to too many machines at once, an operator may allow the sewing-machine head to travel too far along the screw-shaft before stopping it, and this results in the breaking of the needles or such bending 65 of the same as causes poor work to be done on the succeeding seam that is attempted to be sewed by the machine. In order to obviate these difficulties, we have combined therewith an automatic trip device *i*, and this 70 consists of a lever *k*, pivoted to a block *l*, fast to the frame or any fixed part of the machine, the upper arm *k'* of the lever underlying the under side of the shipper-rod *e* and resting in contact therewith. The longer arm *k''* of the 75 lever is connected to the stop-rod *m*, as by passing through a slot in the end of the stop-rod that is supported on uprights *n*, fast to the frame of the machine. To this reciprocating stop-rod *m* there is secured one or 80 more studs *o*, adjustably secured thereto, as by means of a screw-clamp *o'*, and these studs project into the line of movement of the adjustable trip-finger *p*, that is borne on the traveling head *b* of the sewing-machine. This 85 trip-finger is secured in such position to the head that when it is set as illustrated in dotted outline in Fig. 2 of the drawings it will in the forward movement of the sewing-machine head come in contact with the stud *o* 90 and slide the stop-rod along, which sliding movement tilts the lever *k*, and thus lifts the shipper-rod, so that the shoulder is raised above the stop on the bearing *f* and the spring *h* at once throws the shipper-rod over 95 and shifts the belt to stop the machine. This trip-finger is made vertically adjustable by means of the cam-latch *r*, that, in the form of improvement shown, is slotted at the end for the passage of the finger that is held downward by means of the spring *p'*. When the cam-latch is set as shown in Fig. 3, the trip- 100

finger will not operate to move the stop-rod; but by moving the cam-latch forward the finger is projected downward a distance sufficient to cause its lower end to engage the 5 stud in the movement of the head.

We do not limit ourselves to the particular construction or arrangement of the trip-lever or of the trip device, and it is obvious that one or more of the adjustable studs may be 10 used, as may be desired.

In the operation of our device, as soon as the machine-head has been returned to the end of the machine to start upon a seam the resetting of the shoulder of the shipper-rod in engagement with the bearing tilts the stop-lever 15 and sets the stop device in proper position to operate as soon as the machine again is at work, and this sliding of the shipper-rod throws the belt from the loose to the fast 20 pulley and starts the machine.

We claim as our invention—

1. In combination with the movable head bearing the trip-finger, the sliding shipper-rod, the tilting trip-lever with one arm in contact with the shipper-rod and the other arm 25 in contact with the sliding stop-rod, and the projecting stud on the stop-rod located in the path of movement of the trip-finger, all substantially as described.

2. In combination with the movable head 30 of the sewing-machine, the sliding shipper-rod, the vertically-adjustable trip-finger secured to said head, the tilting lever with one arm in engagement with the shipper-rod and the other in engagement with the sliding 35 stop-rod, and the sliding stop-rod bearing the adjustable stud, all substantially as described.

WILLIAM PAULMANN.
HENRY PAULMANN.
